UNITED STATES PATENT OFFICE

163,255

ADVERTISING DEVICE OR SIMILAR ARTICLE

Louis Casper, Richmond Hill, N. Y.

Substituted for design application Serial No. 119,879, June 4, 1945. This application April 28, 1949, Serial No. 2,312

Term of patent 7 years

(Cl. D1—2)

To all whom it may concern:

Be it known that I, Louis Casper, a citizen of the United States, residing in New York city, in the county of Queens and State of New York, have invented a new, original, and ornamental Design for an Advertising Device or Similar Article, of which the following is a specification, reference being had to the accompanying drawing, forming part thereof.

This application is a substitute application for application Serial No. D. 119,879, filed June 4, 1945, now abandoned.

Fig. 1 is a front view of an advertising device or similar article, showing my new design.

Fig. 2 is the rear view of the advertising device or similar article shown in Fig. 1, and

Fig. 3 is a side view of the advertising device or similar article shown in Figs. 1 and 2, on an enlarged scale.

The characteristic features of my new design reside in the portions shown on the drawing in full lines.

I claim:

The ornamental design for an advertising device or similar article, substantially as shown and described.

LOUIS CASPER.
